MAIL SORTING RACK

Frank A. Nuttall, Darien, Conn., assignor to Pitney-Bowes, Inc., Stamford, Conn., a corporation of Delaware

Application August 7, 1952, Serial No. 303,073

1. Claim. (Cl. 211—11)

This invention relates to mail sorting racks and is particularly concerned with the problems of storage, shipping and assembly of devices of this character, as well as the problems of adapting the same to spaces of limited dimensions.

Heretofore sorting racks have been constructed of frames subdivided into columns by vertical partitions, then divided into cells by horizontal shelves or by similarly subdividing a peripheral frame. Devices of this kind do not readily lend themselves to being stored in a knocked-down condition, since substantial cabinet skill is normally required to perform the assembly. Furthermore, such racks are only capable of being used in sizes and arrangements which accord strictly with their predetermined outline dimensions.

An object of the present invention therefore, is to provide a rack composed of elemental cell units so arranged that they can be easily and quickly grouped and connected to form a rack by any mechanically inclined person regardless of the degree of his cabinet making skill, and of such character that a wide variety of shapes and sizes of racks can be built using mainly the same essential parts.

Another object of the invention is to provide a rack built up of narrow cell elements which would normally have relatively inaccessible interiors, but so arranged that interior connections to a support or to adjacent cells can be easily made one at a time through open portions of the elements, the elements cooperating in such manner that each cell is completed or closed by its adjacent partner after the supporting connections have been made.

Another object of the invention is the provision of a rack having cells arranged in such a manner that the material placed therein is in the most convenient position for grasping and inspection, i. e. in an edge supported position, but arranged so that the material will all lean towards one side only of each cell to remain by gravity in a concentrated and readily graspable group.

Still another object of the invention is to provide a sorting rack having cells arranged for on-edge retention of the sorted material, which cells are provided with sliding supporting surfaces at the bottom of each cell for quickly moving the material from a cell-enclosed position partly extending from the cell so as to be readily grasped by the hand of the user.

A feature of the invention is the provision of supporting surfaces for on-edge retention of material, which surfaces have stop members extending in an in-and-out direction of the cell so that material placed in the cell will not tend to slide to one side but will stay in the deposited position leaving room beside it for other material until the space has been properly filled.

Another feature of the invention is the provision of cooperating cell elements and slidable support members or floor elements arranged for cooperating engagement such that no direct connection is provided therebetween, but so shaped that the slidable support is automatically retained in its cell when the latter is closed by the placing of the next adjacent cell-forming element.

2

Still another feature of the invention is the provision of label holders on the slidable supporting surfaces so arranged as to provide a manual grip member for conveniently manipulating the support and related to the cells in such a way that interference between the label holder and the material being sorted is entirely avoided.

With the above and other objects in view, which will appear as the description proceeds, the invention resides in the combination and arrangement of parts and in the details of construction hereinafter described and claimed, it being understood that various changes in the precise embodiment of the invention herein disclosed, may be made within the scope of what is claimed without departing from the spirit of the invention.

15 A preferred embodiment of the invention is illustrated in the accompanying drawings, wherein:

Fig. 1 is a front elevation of a sorting rack according to the present invention.

Fig. 2 is an end elevation of the device of Fig. 1.

20 Fig. 3 is a perspective view to a larger scale of one of the cell-forming elements, together with its corresponding slidable floor element, used in the construction of the device of Fig. 1.

Fig. 4 is a fragmentary section taken substantially on 25 line 4—4 of Fig. 3 but showing the cell-forming element as mounted, and also showing in section a portion of an adjacent element when placed in closing relation to the element of Fig. 3.

Figs. 5, 6, and 7 are front elevations of alternative 30 cell-forming elements which can be used in carrying out the invention.

With reference to the accompanying drawings, the invention is illustrated as including a vertical supporting panel 11 which is appropriately mounted in vertical 35 position, e. g. by connection to supporting brackets 12, and to which are suitably attached a plurality of cell-forming elements 13. As shown in Fig. 3, each of the elements forms a shallow channel essentially reverse C-shaped in front edge view and may be attached to the panel 11 in any suitable fashion so as to project forwardly therefrom with its web or longest member extending in a generally up-and-down direction.

In the preferred form of the invention illustrated in the drawings, each cell-forming element 13 includes a 45 rear wall 15 closing one end of the channel and has fastener openings 17 included therein. Suitable fasteners such as screws 19 passed through the openings 17 and into the panel 11, serve to hold the elements in place on the panel 11.

50 To construct a sorting rack the elements 13 are attached to the support 11 one after another starting with the one farthest to the right and proceeding towards the left until a tier is completed, and additional tiers are similarly formed until the whole of the desired array is completed. The open side of the cell farthest to the left in each tier is closed by means of a filler member 21 attached to the panel 11 by screws 23.

Panels 11 may be readily cut to various sizes so that 55 the tier length and number of tiers of elements 13 will conform to the space requirements of the user of the rack without the necessity for carrying in stock the variety of assemblies that would be necessary with the type of racks heretofore used.

While the elements 13 are shown in the preferred C-shaped form, it will be understood that L-shaped elements 13a as shown in Fig. 5 and providing open topped cells can also be conveniently employed if desired, or Z-shaped elements 13b or 13c as shown in Figs. 6 and 7 in which the horizontal members forming walls of adjacent cells may be employed.

70 Since the cells are preferably narrow and rather deep to accommodate the largest sizes of matter normally sorted,

for example about 12 inches deep in most cases, it will be seen that the fasteners 19 are relatively inaccessible when the assembly is complete. However, since each of the cell-forming elements 13 has an open side, the screws 19 are easily and conveniently placed as each element 13 is applied to its tier, and only become inaccessible after the next succeeding element 13 has been placed. The racks are thus quickly and readily constructed without requiring unusual skill in spite of the hidden position of the fastening elements when the assembly is completed. In the case of the Fig. 6 cell-forming element 13b, the tiers would be built from left to right instead of from right to left.

In the preferred form of the invention illustrated, each of the cell-forming elements has its most extensive wall 25, i. e. the wall extending generally in an up-and-down direction, disposed non-perpendicularly to its bottom wall 27. This angle is preferably between 50° and 75°, and the value of 63° has been determined as the optimum for most purposes. The slope of the wall 25 is upwardly to the right for the convenience of normal right hand operation. The reason for this is that it has been found that paper sheets of normal stiffness must rest against the spread fingers of the hand to some extent if the remote edge is to be accurately guided and controlled by the hand. The slope designated is sufficient to allow the sheet to rest somewhat against the supporting platform formed by the extended fingers of the sorter's right hand and thus to be held out straight for the most expeditious projection into the selected cell. Furthermore, the angle is such that as the material is partially or fully withdrawn from any cell by the right hand of a sorter it is in a position for ready inspection of the writing thereon. The sloping attitude of the cells also serves another purpose in that material deposited in any cell has a definite tendency to fall towards one side so that the material placed within the cell groups itself by gravity into a bundle for ready grasping and does not tend to divide and fall in opposite directions when projected from the cell in a manner about to be described.

Each of the cell-forming elements 13 is provided with a companion movable floor element 29 which rests upon and slides against the adjacent bottom wall 27 of the cell. The floor element 29 is of a width to substantially fill the cell and is provided at one edge with a laterally extending lug 31 which projects beyond the cell wall. As seen in Figs. 3 and 4, each cell-forming element 13 has formed at the base of its upstanding wall 25 a slot 33 which slidably receives the lug 31 of the corresponding floor element 29. The floor element 29 also includes an upstanding guiding flange 35 at the edge opposite to that having the lug 31. The proportions are such that when the next adjacent cell-forming element 13 is put in place, the flange 35 will be in substantial contact therewith and will prevent any lateral movement of the floor element which would be sufficient to effect withdrawal of the lug 31 from the slot 33. Thus the placing of the next adjacent cell-forming element, during assembly of the rack, locks each floor element 29 irremovably to its corresponding cell forming element 13.

The slots 33 are of sufficient length to permit in-and-out movements of the floor elements to a degree such that the outermost end of the floor element 29 can be projected about four inches beyond the front surface of the rack. In this way all sorted matter which has been accumulated in a cell can be projected at once far enough for ready grasping by the hand of the sorter.

The upstanding flange 35 helps to guide the movable floor 29 during its in-and-out sliding movements and guards the sheets carried by the floor 29 against becoming fouled in the crack between the edge of the floor element 29 and the wall 25 of the adjacent cell-forming element, or in the slot 33 of said adjacent wall 25. A rear upstanding flange 37 at the inner end of the slidable

floor 29 acts as a pusher to insure movement of the sorted material with the floor so as to be positively projected to graspable position.

The upper surface of the floor 29 is preferably provided with a plurality of parallel longitudinally extending ridges 39 forming between them grooves 41. These elements serve to retain any matter placed in the cell against sliding towards the lower left hand corner. As the material is placed in the cell it is caught by the ridges and held so that the cell gradually fills up in a lateral direction from right to left, instead of having the pieces of sorted material first placed in the cell slide across the cell at the bottom making it awkward for subsequent pieces to be properly inserted. Furthermore, whenever the material in the cell is pushed to one side to compact it, it will be caught by the ridges 39 and retained in the new displaced position at one side of the cell in so far as practical for the quantity of material present, leaving the desired space for added material. The particular configuration of the ridges 39 shown in the drawings contributes especially to this last mentioned property. The slope at the left side of each ridge is gradual while that at the right side is abrupt so that the edges of material in the cell can be readily slid to the right over the ridges to be caught behind them, and will be returned to the left only with difficulty.

The outermost end of each slidable floor element 29 carries an integral depending flange 43 which lies wholly without the outlines of the cell. It is in a convenient place for ready grasping by the sorter's finger for manipulating the floor element 29 in and out, and likewise provides a convenient position for the application of designating indicia 45 for identifying the contents of the corresponding cell.

It will be noted that the designating members 43 are altogether removed from a position affecting the insertion and withdrawal of material into and from the cells which was not the case with many prior constructions. For this reason in part and to secure the utmost efficiency in general use of the device of this invention, the tiers of elements 13 should be spaced a suitable distance above one another, between one and two inches generally being satisfactory.

From the foregoing description it can be seen that this invention provides a sorting rack which is not only much more economical of storage and shipping space and more flexible in the size and shape of the ultimate assemblies which can be derived from similar components, but one which is also much more useful and efficient than devices previously intended for such purposes.

Having described the invention, what is claimed is:

A mail sorting rack comprising a supporting panel and at least one row of horizontally disposed cellular units open only at their forward ends when assembled, wherein the units generally comprise essentially reverse C channel shaped members assembled with the open side of one member engaging the closed web side of an adjacent member and having the rear portions thereof secured to the panel, and a mail supporting element slidable along the surface of the lower portion of the channel including means to prevent complete withdrawal thereof, whereby the mail supporting element may be withdrawn to provide access to the mail contained thereon.
